REPRODUCER OF PHONOGRAHS

"a." Filed March 23, 1927

FIG. 1.

FIG. 2.

C. H. Davis
INVENTOR

By: Marks & Clark
Atty's.

UNITED STATES PATENT OFFICE

CLAUDE HUDSON DAVIS, OF MOSMAN, NEW SOUTH WALES, AUSTRALIA, ASSIGNOR TO THE RESONATOR LIMITED, OF SYDNEY, NEW SOUTH WALES, A COMPANY OF NEW SOUTH WALES

REPRODUCER OF PHONOGRAHS

Application filed March 23, 1927, Serial No. 177,702, and in Australia December 29, 1926.

The invention relates to a type of phonograph reproducers in which sound vibrations are imparted to a comparatively large ring preferably of cane by a needle which is 5 clamped in a holder upon the ring and follows the sound groove of a disc record in the ordinary manner. The ring has secured within it the larger end of a conical amplifier made of thin material. I have found that to 10 connect the amplifier to the ring by gluing or other similar means is detrimental to the quality of tone and the principal object of the present invention is the connection of the amplifier to the ring by such means and 15 in such way that good quality and volume of tone result.

According hereto the ring has a groove upon its inner circumference and the end of the amplifier is wedged therein by cords 20 of twisted strands of cotton, silk or similar fibre.

There is also provided a bracket for connecting the ends of the material from which the ring is produced, and which bracket also 25 forms one of the elements in apparatus for supporting the reproducer while in use.

In the accompanying drawings:—

Figure 1 is a front elevation.

Fig. 2 is an enlarged vertical cross sectional 30 view through the frame and amplifier.

Figure 3 a side elevation.

Figure 4 is an enlarged vertical sectional 35 detail showing the bracket, spindle head, spindle and pillar when assembled.

Figure 5 is a perspective view of the connecting bracket.

The ring 1, preferably of cane or wood, but 40 which may be of other material such as vulcanite or celluloid, has a groove 2, which receives the end of a conical amplifier 3 of thin material such as wood veneer. The cords 4 and 5 of twisted silk are wedged and glued 45 into the groove upon the inside and outside of the amplifier, the edge of which preferably should not contact with the bottom of the groove.

Cane wedges 6 are used to reinforce the 50 ring and also to assist in the conduct of vibration, at the place where a needle holder 8 is located. The needle holder has a binding

screw 9 which clamps the needle in a socket in the holder and an integral screw threaded portion which screws into the ring at the angle suitable for the needle.

Referring now more particularly to Figures 3 to 5. A bracket 11 fits the curve of the ring and is secured thereto by the bolts 12 and 13. When the ring is not continuous but produced by bending a rod the bracket forms a medium for connecting the ends. 55

The ears 14 pass through slots in the bracket and each has a curved extension 15 which fits a recess 16 in the bracket and is firmly held therein between the bracket and the ring. 60

The ears project through the bracket and are hinged in the head 17 of a supporting spindle 18, turnable freely in a vertical hole in the pillar 19. The underside of the head contacts with the top of the pillar. A pivot 70 pin 20 passes through holes in the ears and through corresponding holes in the head, thereby permitting free movement of the reproducer in a vertical arc. 65

A wood screw 21 is employed to secure the 75 pillar to the phonograph machine. It is deemed preferable to use the cord wedges upon both the inside and outside of the amplifier, but if desired the cord may be used only upon one side its place upon the opposite side being supplied by wedges resembling the wedges 6 spaced at intervals around the ring. 80

I claim:—

1. An acoustic device wherein is combined 85 a ring having a groove on its inner circumference, an amplifier the outer periphery whereof is located in the groove, fibre cord wedging the amplifier within the groove, and a needle holder secured to and connected solely to said ring. 90

2. An acoustic device including in combination a ring having a groove on its inner 95 circumference, an amplifier the outer periphery whereof is located in the groove, fibre cord wedging the amplifier within the groove, a needle holder secured to and connected solely to the ring and wedging means of substantially rigid material located in the 100

groove adjacent where said needle holder is located.

3. An acoustic device including in combination a ring having a groove on its inner circumference, an amplifier the outer periphery whereof is located in the groove, means for wedging the amplifier within the groove and a needle holder secured to and connected solely to said ring.
- 10 4. An acoustic device including in combination a ring having a groove on its inner circumference, an amplifier the outer periphery whereof is located in the groove, means for wedging the amplifier within the groove,
- 15 a needle holder secured to and connected solely to said ring, a bracket connected to said ring, a spindle, means for pivotally mounting said bracket on said spindle, and a pillar having a hole therein extending substantially vertically thereof which receives said spindle.

In testimony whereof, I have this 25th day of February, A. D. 1927 signed my name to this specification.

25 CLAUDE HUDSON DAVIS.
